J. W. KELLY.
FIRE EXTINGUISHER.
APPLICATION FILED DEC. 15, 1919.

1,371,689.

Patented Mar. 15, 1921.

UNITED STATES PATENT OFFICE.

JAMES W. KELLY, OF CHICAGO, ILLINOIS.

FIRE-EXTINGUISHER.

1,371,689.

Specification of Letters Patent. Patented Mar. 15, 1921.

Application filed December 15, 1919. Serial No. 344,779.

To all whom it may concern:

Be it known that I, JAMES W. KELLY, a citizen of the United States, residing at Chicago, in the county of Cook and State of Illinois, have invented a new and useful Improvement in Fire-Extinguishers, of which the following is a specification.

My invention relates more particularly, though not exclusively, to fire extinguishers of what may be called the self-contained type, namely that type in which a liquid, either plain water or water mixed with chemicals, is confined in a receptacle containing means operating when the apparatus is to be used, to place the liquid under pressure for discharging it against the fire, as for example by the use of air-pressure stored in the receptacle; and my primary objects are to provide a novel, simple and relatively inexpensive construction of fire extinguisher which will be better adapted for performing the functions for which structures of this character are provided, which will remain, for the maximum length of time, conditioned for instant use in case of fire, by which the maximum fire-extinguishing effect may be produced; and which will automatically become operative upon the surrounding air reaching a certain temperature.

Referring to the accompanying drawing:—Figure 1 is a view in vertical sectional elevation of apparatus constructed in accordance with my invention, the section being taken at the line 1 on Fig. 3, and viewed in the direction of the arrow. Fig. 2 is a plan view of the apparatus with the fusible plug and deflector-supporting head removed; and Fig. 3 a plan view of the structure as shown in Fig. 1.

In the particular construction illustrated I provide a receptacle 4 preferably in the form of a cylinder 4^a with its upper end closed and of dome-shape as illustrated, and a separate bottom-forming member 5. The portion 4^a of the receptacle is preferably formed by drawing it from a single sheet of steel, whereby its side-wall and upper, dome-shaped, end, are integral, the lower end of the cylinder being preferably formed, by deflecting the metal, with an annular, inwardly-extending, flange 6, forming a seat against which the bottom 5 extends. The bottom 5 is preferably formed with the annularly flanged peripheral portion 7 over which the metal at the extreme end of the cylinder is inwardly and upwardly bent, as

represented at 8, to firmly interlock therewith and produce a tight joint, the bottom section 5 containing a threaded opening 9 having a closure in the form of a plug 10, secured therein, this opening forming the filler opening of the receptacle through which the liquid to be charged into the latter, is introduced. The side-wall of the receptacle, at a point closely adjacent the bottom thereof, is equipped with a pipe-coupling 11 which opens at its inner end into the interior of the receptacle, and at its upwardly extending portion 12 into a pipe 13, the coupling 11 containing in the passage-way therethrough, beyond its communication with the pipe 13, an inwardly-opening check valve (not shown) which permits air, from a supply thereof (not shown) and connected with the end 14 of the coupling 11, to be forced into the receptacle 4 to build up, and maintain, therein a pressure above the liquid for forcing the latter out through the pipe 13 for the purpose, and under the conditions, hereinafter described, there being provided for removably closing the passage in the part 14 of the coupler, at which the air supply is connected for the purpose stated, a plug 15 which may be removed for charging the receptacle with air.

The pipe 13 at its upper end is deflected preferably to the median line of the receptacle 4 and thence upwardly as represented, at which portion it is preferably associated with a brace 16 carried by the receptacle 4, to render this part of the structure relatively rigid. The brace 16 is shown as formed of a pair of arms 17 which are connected with, and diverge from, a head 18 through which the upper end of the pipe 13 extends and closely fits, the lower, enlarged, ends 19 of the arms 17, being secured in flat-wise relation to the adjacent portion of the receptacle 4, as by welding them thereto, it being preferred that the arrangement of the arms 17 relative to the pipe 13 be that shown in the drawings.

Surmounting the head 18 and threaded upon the upper end of the pipe 13, is a cup-shaped, preferably shallow, receptacle 20 for the purpose hereinafter explained, the pipe 13 extending into the receptacle and having secured thereon a yoke 21, presenting the aperture 22 and containing a bore 23 opening into the upper, open, end of the pipe 13. The yoke 21 at the apertured portion 22 is provided with means extending

into the path of the liquid discharged from the receptacle upwardly through the open end of the pipe 13, for deflecting the liquid downwardly against material hereinafter referred to positioned in the receptacle 20, these means as shown being in the form of an inverted dished member 24 secured to the yoke 21 in the aperture 22 thereof to extend directly above the bore 23 in the yoke and concentrically thereof, as by a screw 25 screwing through the member 24 and into the yoke, the edges of the member 24 being preferably fluted as represented at 26. The discharge from the pipe 13 is under the control, in the particular arrangement shown, of a fusible plug, of a character maintaining the pipe 13 closed under normal conditions and automatically releasing upon the temperature of the surrounding air reaching a certain degree, namely a degree indicating the presence of fire in close proximity thereto. These means in the construction shown comprise a plug proper 27 which may be of glass, or any other suitable material, and which closely fits in the outwardly flaring mouth of the bore 23, and a fusible element represented at 29 and formed, as for example of a bar section 30 of brass confined in the slot 31 of the screw 25, and a section 32 connected with the section 30 in alignment therewith and engaging a slot 33 in the upper end of the plug 27, the section 32 being of any desirable material which fuses at the temperature at which it is desired the fire-extinguisher automatically operate, such for example as the material commonly used in the fusible plugs of automatic fire-sprinkler systems.

In conditioning the apparatus for use the liquid to be used, as for example water or water containing chemicals if desired, may be introduced into the receptacle 4 through the filler opening 9, as for example to the height indicated by the line 34, and the receptacle then charged with compressed gaseous material, as, and by preference, compressed air, to build up a relatively high pressure in the upper part of the receptacle, and any suitable chemical, preferably in solid form, and more preferably molded into a solid mass, and represented at 35 and of such character that when mixed with the liquid used, as for example water, will operate to aid in extinguishing the fire, as by a smothering action, charged into the receptacle 20.

The operation of the apparatus is as follows: When the temperature of the air surrounding the apparatus reaches a degree sufficient to fuse the metal of the section

32, the plug 27 is thereby released permitting the compressed air contained in the receptacle 4 to force the liquid therefrom out through the pipe 13 from which it discharges against the deflector 24 which throws the liquid downwardly in all directions against the material 35 in the receptacle 20 from which the water deflects outwardly to spray adjacent surfaces and operate to extinguish the fire, the liquid in washing against the chemical 35 becoming mixed therewith to cause the liquid to have the desired fire-extinguishing property.

The apparatus may be provided with a portion at which it may be suspended or carried about by the user, the construction shown being formed with a bail 100 for this purpose which is pivotally connected with apertured lugs 101 on the sides of the receptacle 4^a.

What I claim as new and desire to secure by Letters Patent is:

1. In fire-extinguishing apparatus, the combination of a passage through which liquid is discharged, a receptacle for a material to become mixed with the liquid, arranged to extend about said passage, and a dished deflector extending in inverted condition over said passage and positioned to deflect the liquid discharging from said passage, downwardly against the material in said receptacle.

2. In fire-extinguishing apparatus, the combination of a passage through which liquid is discharged, a receptacle for a material to become mixed with the liquid, fusible means sealing the discharge end of said passage, and means for deflecting the liquid discharging from said passage, against the material in said receptacle.

3. In a fire-extinguisher, the combination of a receptacle for liquid, a pipe communicating with the lower end of said receptacle and leading upwardly along the side of said receptacle and extending upwardly therefrom at a point substantially centrally of said receptacle, and a brace for said pipe connected with said receptacle and with said pipe adjacent the center of said receptacle.

4. In a fire extinguisher, the combination of a tank for water containing a compressed fluid and having an outlet, a fusible plug restraining the discharge of the water from said tank, and a receptacle exterior of said tank for causing a material which when mixed with water operates to smother fire, to become mixed with the water in the flow thereof from said tank.

JAMES W. KELLY.
